(57) **CLAIM**

The ornamental design for a portable charger, as shown and described.

DESCRIPTION

FIG. 1 is a front elevational view of a portable charger showing the new design;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a first perspective view thereof;

FIG. 8 is a second perspective view thereof;

FIG. 9 is a first perspective view showing the portable charger in an open state; and,

FIG. 10 is a second perspective view thereof showing the portable charger in the open state.

The broken lines shown in the drawings are for the purpose of illustrating portions of the article and form no part of the claimed design.

1 Claim, 10 Drawing Sheets
